York, N. Y., a corporation of Delaware

Original application April 11, 1933, Serial No.
665,501. Divided and this application August
23, 1935, Serial No. 37,483

7 Claims. (Cl. 257—36)

My invention relates to a rectifier for absorption refrigeration apparatus and it is an object of the invention to provide an air cooled rectifier operative without decrease in efficiency throughout a wide range of room temperatures and thermal inputs. This application is a division 5 of my application Serial No. 665,501 filed April 11, 1933.

The invention, together with the objects and 10 advantages thereof, will appear upon consideration of the following description taken in conjunction with the accompanying drawings, of which:

Fig. 1 is a side elevation, partly in vertical section, of a rectifier embodying the invention;

Fig. 2 is a top plan view, partly in horizontal section, of the rectifier shown in Fig. 1;

Fig. 3 is a sectional view taken on the line 3—3 in Fig. 1;

Fig. 4 shows diagrammatically an air cooled 20 absorption refrigeration system provided with the rectifier; and

Fig. 5 is a side elevation, partly in vertical section, of a known rectifier for comparison with that shown in Fig. 4.

Referring to Figs. 1, 2, and 3 of the drawings, a rectifier 10 comprises a pipe which, for the purpose of explaining the invention, I have indicated as consisting of a first part 11, a second part 13, a loop 14, and a third part 15. The parts 11 and 13 are formed by a continuously straight portion 30 of the pipe which is inclined slightly downwardly to the right as seen in Fig. 1. The part 15 is arranged by forming the loop 14, alongside of part 13 and inclined slightly downwardly to the left as seen in Fig. 1. The first part 11 is provided with heat radiation fins 12. The parts 13 and 15 are imbedded in a metal casting 16. The casting 16 provides a good thermal conduction between the parts 13 and 15 and, therefore, is preferably of 40 aluminum. The casting 16 is provided with, or may be formed with heat radiation fins 17. The fins 17 are arranged in thermal conductive relation with only that portion of the casting 16 which is adjacent the part 15 of the pipe. The fins 17 are formed with openings 18 next to the 45 remaining portion of the casting 16. Thus, the part 15 is included in the path of thermal conduction from the part 13 to the fins 17. The end 19 of the rectifier 10 will be referred to as the inlet, and the other end 20 will be referred to as the outlet.

Referring now to Fig. 4 of the drawings, the rectifier 10 is shown connected in a continuous 55 absorption refrigeration system of a pressure

equalized type, as generally disclosed in Patent 1,609,334 to von Platen et al. Operation of the particular system illustrated is briefly as follows:

In a generator 21, ammonia vapor is expelled by 5 heat from the water solution of ammonia contained in the generator. Ammonia vapor passes to the inlet 19 of the rectifier 10. In the rectifier, water vapor condenses out of the ammonia and drains back to the generator. The ammonia vapor passes from the outlet 20 of the rectifier 10 into an air cooled condenser 22. In the condenser, the ammonia vapor is liquefied and the liquid ammonia drains into vessel 23. From the lower part of the vessel 23, the liquid ammonia overflows through a conduit 24 into an evaporator 15 25 where it evaporates and diffuses into hydrogen which enters the evaporator through conduit 31. The resulting gas mixture flows from the evaporator through conduit 26, a gas heat exchanger 27, and a conduit 28 into an absorber 34. Here 20 the ammonia is absorbed out of the gas mixture into weakened solution which enters the absorber through a conduit 29. The resulting weak gas returns from the absorber to the evaporator through a conduit 30, the gas heat exchanger 27, 25 and the conduit 31. The enriched solution flows from the absorber through a conduit 35, a liquid heat exchanger 33, and a thermosyphon conduit 36 into the generator 21. The weakened solution 30 flows from the generator 21 to the absorber 34 through a conduit 32, the liquid heat exchanger 33 and the conduit 29.

The absorber 34 is cooled by a system comprising a cooling coil 37 around the absorber and a condenser 38, the cooling coil and condenser being interconnected to form a closed circuit which contains a suitable cooling fluid, such as methyl chloride, which evaporates in the coil 37 and liquefies in the air cooled condenser 38, thus providing a vaporization-condensation cycle for 35 transferring heat from the absorber to the air.

The condenser 22 is vented to the gas circuit to return trapped hydrogen. A vent is provided by a conduit 39 connected from the upper part of the vessel 23 to the absorber 34 and having an enlarged chamber which may be referred to as a pressure vessel 40. The pressure vessel provides storage space for auxiliary hydrogen which is displaced into the gas circuit between the absorber and evaporator at high air temperatures, thereby increasing the total pressure in the system 45 so that the latter varies in accordance with room temperature.

For the purpose of better understanding the present invention, assume, for the present, that 55

a known rectifier 41, as illustrated in Fig. 5, is connected in the above described system in place of the improved rectifier 10. The rectifier 41 is provided with heat radiation fins 42, and is of such length that all of the water vapor is condensed out of the ammonia before the latter enters the condenser 22 when the system is operating with maximum heat input at maximum room temperature. If the rectifier 41 should be too short, some water vapor will pass into the condenser and evaporator, involving a heat loss or decrease in refrigerating efficiency. When this system is operating with a low heat input at low room temperature, all the water vapor will have been condensed out of the ammonia in the first part of the rectifier 41. At minimum room temperature with minimum heat input, all of the water vapor may be condensed in the first half of the rectifier 41, and in the remaining length of the rectifier ammonia vapor will condense, the liquid ammonia draining back to the generator through the rectifier inlet 19, thus decreasing the efficiency of the system.

In accordance with my invention, however, the improved rectifier 10 is connected in the system shown in Fig. 4 in place of the known rectifier 41. The first part 11 of the rectifier 10 is so dimensioned that at minimum room temperature with minimum heat input all water vapor will be removed from the gas but no condensation of ammonia will take place. The second part 13 is cooled by the fins 17 only by conduction of heat through the third section 15. It will now be clear that there must be a temperature drop from the rectifier section 13 to the third section 15 and that the section 13 will always be at a temperature above that of section 15. When the rectifier section 15 is cooled to a sufficiently low temperature, it functions as a condenser for the ammonia vapor, and under such conditions may be considered as a condenser, for instance, the first part of condenser 22. It will now be further understood that the rectifier section 13, being at a higher temperature than the section 15, must always remain at a temperature above the condensing temperature of ammonia. Liquid formed in parts 11 and 13 of my rectifier drains back to the generator. Liquid formed in the part 15, however, drains to the condenser 22. Thus, all the water vapor will be removed from the ammonia in the rectifier 10 at maximum room temperature with maximum heat input, but at minimum temperature with low heat input no ammonia will be condensed where it can drain back to the generator.

It will be understood that various changes may be made within the scope of the invention which is not limited except as indicated in the following claims.

60 What is claimed is:

1. A rectifier for an absorption refrigeration

system having portions arranged for flow of liquid in opposite directions, heat radiation means, and means for transferring heat from one of said portions to said radiation means by conduction in a thermal path including another of said portions. 5

2. A rectifier for an absorption refrigeration system having portions arranged for flow of liquid in opposite directions, and means for conveying heat from one of said portions by conduction in 10 a thermal path including another of said portions.

3. A rectifier comprising an inclined tube, heat radiating fins on the lower part of said tube, a second tube having one end connected to the upper end of said first tube, and an aluminum 15 casting embedding the upper part of said first tube and said second tube, said casting being provided with integral heat radiating fins extending from that portion adjacent said second tube. 20

4. A rectifier for an absorption refrigeration system including a looped conduit having the portions on opposite sides of the loop in thermal exchange relation and arranged for flow of liquid in opposite directions in said conduit, and heat 25 radiation means directly associated with only one of said portions.

5. A rectifier for an absorption refrigeration system including a looped conduit having portions on opposite sides of the loop embedded in 30 a body of thermal conductive material and arranged for flow of liquid in opposite directions in said conduit, said body having a heat radiation surface for air cooling adjacent one of said portions and remote from the other of said por- 35 tions.

6. A rectifier for an absorption refrigeration system including a conduit having a first portion provided with extensive heat radiation surface for air cooling and a second portion and a third portion, means providing a further heat radiation surface for air cooling, and means providing a thermal conductive path to said further heat radiation surface from said second portion of said rectifier conduit intermediate said first and third portions, said third portion being located wholly in said path between said second portion and said further radiation surface. 40 45

7. A rectifier for an absorption refrigeration system including a conduit having a plurality of 50 portions each constructed and arranged for transfer of heat from within by conduction and radiation to a cooling medium outside, two of said portions having a common path for conduction of heat to a common radiation surface, one of said two portions being located wholly between the other of said two portions and said radiation surface whereby said other of the two portions remains at a temperature above that of the first of said two portions. 55
